UNITED STATES PATENT OFFICE.

JAMES W. BROWN, JR., OF CAMDEN, ARKANSAS.

SPARK-PLUG.

No. 010,123.

Specification of Letters Patent.

Patented April 20, 1900.

Application filed September 23, 1898. Serial No. 464,803.

To all whom it may concern:

Be it known that I, JAMES W. BROWN, Jr., a citizen of the United States, residing at Camden, in the county of Ouachita and State 5 of Arkansas, have invented certain new and useful Improvements in Spark-Plugs, of which the following is a specification.

This invention relates to sparking apparatus for hydrocarbon engines, or the like, and 10 has particular reference to the construction of a spark plug, the electrodes of which are of peculiar and advantageous construction as will be hereinafter fully set forth and as illustrated in the accompanying drawings, in 15 which—

Figure 1 is an elevation, partly broken away, illustrating a suitable form of spark plug embodying one form of the present invention; Fig. 2 is a detail sectional view on 20 the line 2—2 of Fig. 1; Fig. 3 is fragmentary view similar to that of Fig. 1, to illustrate a modified form of the electrodes, and Fig. 4 is a view similar to Fig. 3 indicating a still further modification.

Throughout the following detail description and on the accompanying drawings, similar parts are referred to by similar reference characters.

In carrying out this invention and with 30 particular reference to Figs. 1 and 2, 10 indicates a metallic bushing adapted to be connected by means of screw threads 11 to an ordinary type of explosive engine (not shown). Extending longitudinally through 25 said bushing is an insulated sleeve 12, made of porcelain or the like, and within said sleeve is a metallic stem 13, at the upper end of which is a binding nut 14 for attachment of one terminal of the electric circuit. The 40 lower or inner end of said stem 13 is provided in any suitable manner with a short axis 15 which extends at any suitable angle, preferably a right angle, to the main axis of the stem 13 and spark plug as a whole. Journaled for rotation upon said short axis 15 is a 45 button-shaped electrode 16. This electrode is of thick, heavy metal at its hub or center, and its periphery is circular and in the form of a knife edge 17.

Located adjacent to the inner terminal of the stem 13 and the electrode 16 and supported in or to the inner end of the bushing 50 is an axis 18, and journaled for free rotation on said axis 18 is a second electrode 19, similar in size and form to the aforesaid electrode

16. As illustrated in these figures the axes of the electrodes 16 and 19 are disposed substantially at right angles to each other and consequently the planes of the electrodes journaled thereon intersect each other. By 60 this arrangement those portions of the electrodes which are directly opposed to each other are practically points, insuring a sharp hot spark. A primary purpose in forming the electrodes of heavy material as illustrated is to provide for an accumulation of a heavy charge of electricity adjacent to the 65 sparking points. The electrodes, journaled as indicated, will be caused, by the vibration of the engine and the rush of gases to and from the spark plug, to rotate on their axes, whereby deposition of soot thereon and which would tend to interfere with proper 70 sparking or to cause short circuiting, will be prevented, and furthermore the rotation of 75 the electrodes will insure the presentation of fresh contact surfaces or points for the free transfer of the electric spark.

In the construction illustrated in Fig. 3 the essential features are similar to those 80 previously described. In this construction the same form of bushing 10, sleeve 12, stem 13, and electrode 16, are employed as in the previous instance. The support 18' secured 85 in the inner end of the bushing 10 differs from the corresponding element above described in being disposed substantially parallel to the axis 13, and the electrode 19' journaled on said axis 18' is spoon-shaped or in the form of a double cone, the knife edge 90 17 of the electrode 16 extending within the V-groove of said electrode 19' and is spaced at a definite distance therefrom.

In Fig. 4 is illustrated a slightly different 95 modification wherein the electrode 16 is supported as in the previous cases, for free rotation upon the axis at right angles to the main stem 13 and main axis of the spark plug, but the opposite or negative electrode is in the form of a stationary point 20 secured and 100 supported upon the inner end of the bushing 10 so as to present its point at a definite fixed distance from the knife edge 17 of the rotary electrode. In this construction the electrode 20 comprises an enlarged head for the 105 accumulation of a heavy charge of electricity.

Having thus set forth the characteristic 110 features of this invention, but without desiring to be limited except as required by the

state of the art and the claims hereinafter made, what I claim and desire to secure by Letters Patent of the United States, is:

1. In a spark plug, the combination of a bushing, an insulated sleeve therein, a contact stem extending through the sleeve, the stem having a short axis at an angle to the main axis of the stem and plug, a button-shaped electrode journaled for rotation on said angularly disposed axis of the stem, and another electrode supported upon said bushing and spaced at a fixed distance from the edge of the rotary electrode aforesaid.
2. In a spark plug, the combination of a bushing, an insulated sleeve therein, a contact stem extending through the sleeve, the stem having a short axis at an angle to the main axis of the stem and plug, a button-shaped electrode journaled for rotation on said angularly disposed axis of the stem and having a knife edge, a transversely disposed axis supported by the bushing proximate to said electrode, and a second electrode jour-

naled upon said axis and thereby spaced at a fixed distance from the first electrode. 25

3. In a spark plug, the combination of a bushing, an insulated sleeve therein, a contact stem extending through the sleeve, the stem having a short axis at an angle to the main axis of the stem and plug, a button-shaped electrode journaled for rotation on said angularly disposed axis of the stem and having a knife edge, an axis disposed at an angle to said first mentioned axis and supported by said bushing, and a second button-shaped electrode journaled on said last mentioned axis and having a knife edge in a plane at an angle to the plane of the edge of the first electrode and spaced at a definite distance therefrom. 40

In testimony whereof I affix my signature in presence of two witnesses.

JAMES W. BROWN, JR.
